O. A. ROSS

AUTOMATIC TRAIN CONTROL SYSTEM OR THE LIKE

Original Filed April 20, 1921

FIG 2

FIG 1

Inventor

Oscar A. Ross

By his Attorney

Lyman E. Dodge

UNITED STATES PATENT OFFICE.

OSCAR A. ROSS, OF NEW YORK, N. Y., ASSIGNOR TO GENERAL RAILWAY SIGNAL COMPANY, OF GATES, NEW YORK, A CORPORATION OF NEW YORK.

AUTOMATIC TRAIN-CONTROL SYSTEM OR THE LIKE.

Application filed April 29, 1921, Serial No. 462,801. Renewed April 19, 1927.

My invention relates particularly to that division of automatic train control known as the "means for obtaining the indication from the right of way to a vehicle, or moving train" and has for its more prominent objects the production of a simpler, more efficient, and more reliable means for accomplishing the result desired.

My invention relates more particularly to 10 the class of "means for obtaining the indication from the right of way to the train" known as inductive systems; namely, where the indication is given from the right of way to train by means of induced current as said 15 train passes over one, or more of the inductors on the right of way.

As systems of this kind operate on what is termed the "open circuit principle" it is necessary to check the presence of the inductors 20 and inductive means influenced thereby, including all wires, circuits, etc. involved in successful operation of such a system. One aim of my invention is to entirely check the integrity of such apparatus and circuits 25 whereby it is assured they will be in proper place and in proper operative condition at all times.

All the above and other objects sought are attained by the system which, for purposes 30 of specific illustration, is shown in the accompanying drawings, in which;

Fig. 1, is a diagrammatic view of a section of a roadway equipped with the circuits and apparatus involved in indicating inductively 35 to a moving train, or vehicle.

Fig. 2, is also a diagrammatic view of the circuits and apparatus carried by a train, or vehicle which is adapted to co-operate with the circuits and apparatus illustrated in 40 Fig. 1.

None of the several appliances employed in this system, are, need be of any special, or unusual form, or construction, but for a more ready understanding of the system and of its 45 operation, a preliminary description of the devices, or appliances employed may be appropriate.

Referring to Fig. 1, the rails 1—1, form a railway system of which blocks, A, B, and C, 50 are shown insulated by insulating joints 2—2. Each block is equipped with a track battery such as 2A, and 2B, or their equivalent and track relays such as 3B, and 3C, or their equivalent. Relay 3C, is arranged to oper-

ate or influence controlling levers 4, 5, 6, and 55 7, and relay 3B, levers 8, 9, 10, and 11. Signals such as 12B, and 12C, are arranged at the entrance to each block for indicating to trainmen the speed performance through 60 said blocks. They are controlled in a manner well known to those skilled in the art. It is sufficient to say that if a block as C, is occupied by a train as X1, signal 12C, will be at 65 stop as shown. Further, through influence of signal 12C, signal 12B, is made to indicate 70 caution as shown. 14A, and 14B, are inductive devices composed of a suitable magnetic core, each pole of which is secured to the opposite track rails 1—1, but suitable means such as insulation 50 may be inserted to prevent short circuiting of the track circuits. Said devices are supplied with suitable windings, such as 15, as shown.

Referring to Fig. 2, X2, represents a vehicle, or train of which only one pair of wheels and an axle are shown. Located on said wheels and axle and surrounding the axle is coil 16, which may be called an inductive device or a receiver or an inductive receiver arranged in such a manner that any magnetic flux passing through said axle will effect or 75 induce an electric current in said coil 16.

Also located on the vehicle is relay or electro-magnetic device 17, of suitable coil and core, with its armature arranged to operate 80 contact lever 18. Also located on the vehicle is relay 19, operating lever 20. Also located on the vehicle and controlling the brakes thereof is the electro-pneumatic valve EPV. This may be any of the well-known forms of 85

train controlling devices operating to control the speed of a train, preferably of the construction as illustrated in Patent #1,072,507 granted to me Sept. 9th, 1913, and is known as the stick type, that is, after 90 the circuit controlling the valve is opened externally, the action of the valve in operating to stop the train also maintains said circuit open at a point remote from the point where it is initially opened. Latch 46, pivoted at 95

49, is adapted to allow armature 18 to rise but prevent its lowering to close the circuit until key operated stop 47 has been rotated sufficiently to permit latch 46 to lower below a horizontal plane.

Battery 21, supplies energy for the devices carried by the vehicle.

The operation of my system is as follows;

normally the following track circuit is maintained:

Non-indicating circuit.

- 5 From battery 2B, wire 22, track rail 1, wire 23, relay 3B, wire 24, lever 8, wires 25, 26, coil 15, wire 27, lever 9, wire 28, rail 1, wires 29, 30, lever 7, in upper position, wire 31, returning to battery 2B. With this circuit established, relay 3B is energized and if signal 12B, were not influenced by signal 12C, it would show clear. The amount of energy through relay 3B, is comparatively very small due to inherent conditions existing in a track 15 circuit and which is known as "leakage". For example it is well known that in average track circuits only a small percentage of the energy imposed upon the energy end is delivered at the relay end. Under these conditions 20 the small amount of energy passing through the inductive device, as 14A, is not sufficient to magnetize its core to an extent that will induce an operative current in the cab circuit of a train as X2, while it is passing even at 25 maximum speed, and as will be more fully hereinafter described.

- Assume now that a train, as X1, occupies block C, thereby "shunting out" relay 3C, causing its contact levers to fall to back contact as shown. Under these conditions relay 3B, is energized by a circuit, including the coil 15, of inductive device 14B, in the following manner; from battery 2B, wire 22, rail 1, wire 23, relay 3B, wire 24, lever 8, wires 25, 35 26, coil 15, of inductive device 14A, wire 27, lever 9, wire 28, upper rail 1, wire 29, lever 6, wires 45, 32, coil 15, of inductive device 14B, wire 33, lever 5, wire 34, returning to battery 2B. It will be noted that in the last 40 named circuit the integrity of windings 15, of both inductive devices 14A, and 14B, are checked, as should the circuit of either be opened, relay 3B, would be de-energized.

- Assume now that a train, as X2, enters 45 block B, traveling in the direction of arrow W. Since train X1, has placed inductive device 14B in series with battery 2B, through action of relay 3C, as the wheels and axle carrying coil 16, bridge rails 1-1, of block 50 B, said battery 2B, is short circuited through said wheels and axle forming the following circuit:

Indicating track circuit.

- 55 From battery 2B, wire 22, rail 1, wheels and axle of train X2, upper rail 1, wire 29, lever 6, wire 32, coil 15, of inductive device 14B, wire 33, lever 5, wire 34, to battery 2B. In this manner a large current is sent through 60 the coil 15 of inductive device 14B, and said current increases rapidly as said train X2, approaches said inductive device 14B, and is maximum just as the coil 16 passes over coil 15. Under these conditions coil 15 of inductive device 14B, induces a strong magnetic

flux in its core, and as wheels and axle of train X2, pass over said inductive device a complete magnetic circuit will be formed momentarily through the core, rails, wheels and axle. This circuit is immediately broken as 70 the wheels pass by said inductive device. In this manner a strong current is induced in coil 16, dependent upon the speed at which the said train is traveling. The path of said current is as follows:

75

Cab operating circuit.

From coil 16, wire 35, checking relay 19, wires 36, 37, valve EPV, wire 38, lever 18, wires 39, 40, cab relay 17, wire 41, returning 80 to coil 16. It will be noted that the inductive device 14B, is placed some distance in advance of signal 12C. This distance should be such that if the engineman has obeyed the caution signal and brought the speed of the 85 train, X2, to 20 miles per hour or less, then an automatic application of the brakes will cause its stopping on or before reaching signal 12C. The tension of spring 48 attached to lever 18 will be so adjusted that when a 90 train as X1 passes over an inductive device, as 14B, at a speed in excess of 20 miles per hour, the armature 18 will be raised sufficiently to latch over latch 46. Therefore should a trainman violate the caution signal 95 12B, and attempt to maintain maximum speed through block B, any speed in excess of 20 miles per hour when passing the inductive device as 14B will cause relay 17 to operate and apply the emergency brakes to 100 the train, such emergency application being of such a character that said train will be stopped before reaching signal 12C, even if it be traveling at maximum speed. Latch 46 prevents the closure of the circuit controlled 105 by 18 except after a manual operation of 47.

As the last described circuit is on the open circuit principle, it becomes necessary to check the presence and integrity of all wires, apparatus, etc; therefore the following circuit is maintained:

Cab checking circuit.

From battery 21, wire 42, lever 20, wires 43, 39, lever 18, wire 38, valve EPV, wires 37, 44, 115 returning to battery 21. It will be noted this circuit can be opened through two sources, the lowering of lever 20, which would be caused by an opening of the circuit containing the coil 16, or by raising of lever 18, which 120 would be caused by current of a substantial amount passing through relay 17. Therefore should a wire break, or should the circuit be otherwise opened, relay 19 would be de-energized thereby operating valve EPV, and stopping the train, calling attention to such defect in the circuit.

As stated above the armature 20 is included in the circuit through the valve so that if armature 20 drops the valve will be opened 130

by the opening of its circuit so that the integrity of the coil 16 is always checked because in order to energize relay 19 so that its armature will be in the upper position it 5 is necessary to maintain a circuit from battery 21 through the coil 16 as follows: battery 21, wire 36, relay 19, wire 35, coil 16, wire 41, relay or electromagnetic device 17, wire 40, also wire 43, armature 20 and wire 10 42 to the other side of the battery 21. This last described circuit is a part of the means for checking the integrity of the vehicle carried devices, and operates equally with the circuit through the valve as a detector of 15 circuit integrity and when there is a lack of integrity an operation of the valve or train control device will be caused.

The invention as I have indicated, does not depend upon the use of any specific form of 20 apparatus for accomplishing the functions and purposes hereinbefore set forth.

What I claim is:—

1. In a system of automatic train control, in combination; an inductive receiver; a 25 source of current; a relay, including a controlled circuit controller; an electro-magnetic device; means connecting the source of current, the receiver, the relay, the electro-magnetic device and the circuit controller in a 30 series circuit and means controlled by the electro-magnetic device for controlling the train.

2. In a system of automatic train control, in combination: an inductive receiver; a 35 source of current; a relay, including a controlled circuit controller; an electro-magnetic device, including a controlled circuit controller, means connecting the source of current, the receiver, the relay, the electro-magnetic 40 device and the circuit controller in a series circuit; an electro-magnetic train control device; means connecting the train control device, the circuit controller of the electro-magnetic device, the circuit controller of 45 the relay and the source of current in a series circuit and means to inductively affect the receiver.

3. In a system of automatic train control, in combination: an inductive receiver; a 50 source of current; a relay, including a controlled circuit controller; an electro-magnetic device, including a controlled circuit controller; means for locking said last mentioned circuit controller in one position and manually releasing it to another position; means connecting the source of current, the receiver, the relay, the electro-magnetic device and the first mentioned circuit controller in a series 55 circuit; an electro-magnetic train control device; means connecting the train control device, the circuit controller of the relay, the circuit controller of the electro-magnetic device and the source of current in a series 60 circuit and means to inductively affect the receiver whereby the circuit controller of the 65

electro-magnetic device is moved to locked position and the train control device is deenergized.

4. In an automatic train control, in combination: a trackway; a train control device; an electro-magnetic device for controlling said control device, whereby an energization thereof causes the train control device to act to decrease the train speed; an inductive receiver; means on the trackway for inducing a current in said inductive receiver and means connecting the inductive receiver with the electro-magnetic device, said means including a device for detecting integrity whereby it is rendered safe to depend upon an energization from the trackway to decrease the speed of a train.

5. In an automatic train control, in combination: an inductive receiver; means for inducing a current in said inductive receiver; means for utilizing the said current for controlling the speed of a train; a source of current and electro-magnetic devices and electrical connections therebetween including the receiver whereby the induced current may 90 flow in a circuit not including a source of current, but a current flow through the receiver is maintained to check the integrity of the receiver and the electrical connection.

6. In a system of automatic train control, in combination: an inductive receiver; a source of current; a relay having an armature controlling a make and break contact; an electro-magnetic device having an armature controlling a make and break contact; an electro-magnetic train control device; means connecting the source of current, the armature and make and break contact of the relay, the armature and make and break contact of the electro-magnetic device and the electro-magnetic train control device in a 100 series circuit; and means connecting the receiver, the electro-magnetic device, its armature and make and break contact controlled thereby, the electro-magnetic train control 105 device, the relay and the receiver in a series circuit.

7. In a system of automatic train control, in combination: an inductive receiver; a source of current; a relay having an armature controlling a make and break contact; an electro-magnetic device having an armature controlling a make and break contact; an electro-magnetic train control device; means connecting the source of current, the armature and make and break contact of the relay, the armature and make and break contact of the electro-magnetic device and the electro-magnetic train control device in a 115 series circuit; means connecting the receiver, the electro-magnetic device, its armature and make and break contact controlled thereby, the electro-magnetic train control device, the relay and the receiver in a series circuit, and means connecting the source of current there- 120

by, the receiver, the electro-magnetic device, the make and break contact controlled by the armature of the relay and the armature of the relay in a series circuit.

5 8. In a train control device, in combination: an inductive device including a coil; a train control device; a relay including an armature; two circuits, one including the train control device and the other including a 10 coil of the inductive device the relay and the relay armature and means included in said circuits whereby a lack of integrity causes an operation of the train control device.

9. Car-carried apparatus for automatic 15 train control systems comprising, a car-carried impulse receiving coil for receiving impulses from suitable spaced trackway devices; normally energized electro-magnetic brake control apparatus which if de-energized 20 effects an application of the brakes of the train; an electro-responsive device connected in circuit with said impulse receiving coil for actuating said brake control apparatus, which device if momentarily actuated re-

mains in its actuated condition until restored 25 by separate means; and other means for checking the integrity of the circuit including said electro-responsive device and said impulse receiving coil.

10. Car-carried apparatus for automatic 30 train control systems comprising, a car-carried impulse receiving coil for receiving impulses from suitable spaced trackway device; normally energized electro-magnetic brake control apparatus which if de-energized 35 effects an application of the brakes of the train; an electro-responsive device connected in circuit with said impulse receiving coil for actuating said brake control apparatus, which device if once actuated remains in its actuated 40 condition until restored by separate means; and a relay normally energized and including in series a source of current, its own front contact, said impulse receiving coil and said electro-responsive device, for checking the 45 integrity of such circuit, whereby momentary lack of integrity will be checked.

OSCAR A. ROSS.
